CLAIM

The ornamental design for a task shade, as shown and described.

DESCRIPTION

FIG. 1 is a front perspective view of a task shade supported for use, showing our new design.

FIG. 2 is a front view of the task shade.

FIG. 3 is a rear view of the task shade of FIG. 2.

FIG. 4 is a right side view of the task shade of FIG. 2.

FIG. 5 is a left side view of the task shade of FIG. 2.

FIG. 6 is a top view of the task shade of FIG. 2.

FIG. 7 is a bottom view of the task shade of FIG. 2; and, FIG. 8 is an additional perspective view of the task shade supported for use.

The broken line showings of a task shade stand form no part of the claimed design.

1 Claim, 6 Drawing Sheets
